UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING MACHINES.

Application filed September 26, 1921. Serial No. 503,429.

To all whom it may concern:

Be it known that I, JAMES R. MOFFATT, a citizen of the United States, residing at Chicago, in the county of Cook, State of Illinois, have invented certain new and useful Improvements in Looper Mechanism for Sewing Machines, of which the following is a description, reference being had to the accompanying drawing, and to the figures of reference marked thereon.

The invention relates to new and useful improvements in looper mechanisms for sewing machines, and more particularly to a thread carrying looper having a needle avoiding movement as well as a movement into and out of the needle thread loop.

An object of the invention is to provide a variable looper movement wherein all of the movements imparted to the looper are derived from a single lever.

A further object of the invention is to provide a looper mechanism of the above type wherein the fulcrum for the actuating lever which imparts all the movements to the looper, may be shifted endwise of the lever for varying the movements imparted to the looper through said lever.

A still further object of the invention is to provide means for positively shifting the connection of the fulcrum to the lever and for holding said fulcrum in adjusted positions.

These and other objects will in part be obvious and will in part be hereinafter more fully disclosed.

In the drawings which show by way of illustration one embodiment of the invention—

Figure 1 is a view partly in side elevation and partly in vertical section showing a portion of a sewing machine embodying my improvements;

Fig. 2 is a sectional view on the line 2—2 of Fig. 1;

Fig. 3 is a sectional view on the line 3—3 of Fig. 2, and

Fig. 4 is a perspective view of the rear end of the looper supporting shaft showing the manner of mounting the same and also showing detached the operating lever for imparting movements to the looper supporting shaft and the fulcrum supporting arm therefor.

The invention is directed to a machine

having a work supporting arm for stitching tubular articles, and particularly a type of machine wherein the work supporting arm is carried by a vertically extending member, and wherein the looper or loopers are carried by a looper supporting shaft which is not only oscillated, but moved endwise through a single lever, said lever being connected intermediate its ends to a fulcrum arm. This fulcrum arm is capable of endwise movements, oscillating movements and turning movements, so that an eccentric member attached to the lever not only oscillates the lever so as to move the looper supporting shaft back and forth endwise, but also moves the lever endwise so as to oscillate the looper supporting shaft.

A machine of this general type, and to which my invention is shown applied, is disclosed in the patent granted to Lansing Onderdonk, December 18, 1906, No. 839,077. I have only shown sufficient of the machine in the drawings to make clear the invention, it being understood that reference will be made to said patent for an understanding of the complete machine.

The machine includes a horizontally extending arm 1 having a vertically extending post or supporting member 2 rising from the end thereof, and on the upper end of this vertically extending post is a forwardly projecting work supporting arm 3. The needles 4 and 5 are carried by a needle bar 6 which is reciprocated in the usual way, and these needles operate upon the material at the outer end of the work supporting arm 3. The work is held on the work supporting arm by means of a presser foot 7 carried by a presser bar 8. The present machine is shown equipped for felling, and a feller 9 is placed in front of the presser foot 7. The material is fed off from the end of the work support by means of a feed dog 10. This feed dog 10 is carried by a feed bar 11. The feed bar 11 is pivoted at 12 to links 13. These links 13 are pivoted at 100 their lower ends to a lever 14. The lever 14 is fulcrumed to swing about a support 15 and is oscillated on said support by means of a link 16. This link 16 is connected to an eccentric strap 17 which operates with an eccentric on the shaft 18. When the shaft rotates this link 16 through the lever 14 raises and lowers the feed bar

11. The feed bar at its rear end slides back and forth on the supporting pin 19. The feed bar is moved endwise by means of a link 20 which is adjustably connected to 5 a lever 21 pivoted at 22. This lever is oscillated by means of a link 23 which in turn is connected to an eccentric strap 24 cooperating with an eccentric on the shaft 18. This feeding mechanism per se forms 10 no part of the present invention, but is shown, described and claimed in my co-pending application, Serial No. 503,430, filed of even date herewith.

Cooperating with the needle 4 beneath the 15 work support is a looper 25. Cooperating with the needle 5 is a looper 26. These loopers 25 and 26 are thread carrying loopers and are mounted in a looper carrier 27 which in turn is fixed to the end of a shaft 28. This 20 shaft 28 is mounted so as to oscillate freely and also move endwise in suitable bearings, one near the forward end of the arm 3 and another in the vertical post 2. In Fig. 4 of the drawings, the sleeve bearing in the post 25 2 is indicated at 29. Fixed to the looper supporting shaft 28 is a collar 30 which is clamped thereon by means of a clamping screw 31. Projecting from the collar 30 is an arm 32 which is provided with a ball 33. A lever 34 is provided with a bracket 35 at 30 its upper end having a socket 36 for the ball 33. A cap plate 37 also engages the ball 33 and forms a ball socket therefor. The lever 34 is provided with a head 38 at its 35 lower end having a ball socket 39 adapted to engage a ball 40 on a crank arm 41. This crank arm 41 is carried by a sleeve 42 which is fixed to the end of the shaft 18.

Mounted on said lever intermediate the 40 ends thereof is an adjustable sleeve 43. Said sleeve 43 has a laterally projecting lug 44 into which is threaded a screw 45. This screw 45 is provided with a slotted head 46 and a collar 47 spaced slightly therefrom so 45 as to engage between the forked arms 48 formed integral with the bracket 35. These collars prevent the screw from moving endwise relative to the bracket so that upon turning the screw, the sleeve 43 will be positively shifted endwise of the lever 34. Said 50 sleeve 43 is a split sleeve, and is positively clamped to the lever by means of a screw 49. Projecting from the sleeve 43 is a perforated lug 50. A fulcrum arm 51 is provided with 55 a forked end adapted to straddle the sleeve 50 and is secured thereto by means of the pin 52. This fulcrum arm 51 is freely mounted in a sleeve 53 so that the arm may move endwise in the sleeve, and can oscillate 60 in said sleeve. The sleeve 53 is in turn rigidly secured to a head 54 carried by the stem 55 mounted in a bearing sleeve 56 in the vertical arm 2. On the outer end of the stem 55 is a collar 57 and a lock nut 58. 65 This stem 55 is free to oscillate in the bear-

ing 56 which permits the sleeve 53 to oscillate about the center of the stem 55 as an axis.

The operation of the machine is thought to be obvious from the above description. 70 As the shaft 18 rotates, the lever 34 at its lower end will move in a circle. The fulcrum of the lever is confined to movements up and down in a vertical plane so that the lever 34 oscillates on said fulcrum and 75 moves endwise with the fulcrum. This imparts an elliptical movement to the ball 33 and gives in turn to the loopers both the needle avoiding movement and a movement into and out of the needle thread loops. So 80 far as the operation of the loopers are concerned, they are similar to that set forth in the Onderdonk patent referred to above.

The present invention is directed particularly to the means for shifting the fulcrum 85 in order to vary the extent of movement given to the looper. By loosening the screw 49, and turning the screw 45, the sleeve 43 may be moved endwise of the lever 34. This shifting of the sleeve is positively obtained 90 by the turning of the screw 45, and the connection of the fulcrum to the lever is positively secured in its adjusted positions by means of the screw 49. When this sleeve is moved endwise of the lever, it will vary the 95 amount of lateral movement imparted to the loopers, and this is accomplished without any changing of the movement of the looper into and out of the needle thread loops.

It is obvious that minor changes in the 100 details of construction and the arrangement of the parts may be made without departing from the spirit of the invention as set forth in the appended claims.

Having thus described the invention, what 105 I claim as new and desire to secure by Letters-Patent, is:—

1. A looper mechanism for sewing machines including in combination, a looper, a looper supporting shaft carrying said looper, a lever constructed and arranged so as to impart to said looper supporting shaft oscillating and endwise movements for giving to the looper a needle avoiding movement and a loop taking and shedding movement, a single fulcrum support for said lever, and means for shifting the position of the fulcrum support on the lever for varying the extent of lateral movement only 110 imparted to the looper.

2. A looper mechanism for sewing machines including in combination, a looper, a looper supporting shaft carrying said looper, a lever connected to said looper, an operating shaft extending at right angles to the looper supporting shaft, a crank carried by said operating shaft to which said lever is connected, a single fulcrum support connected to said lever intermediate the ends thereof and arranged so that said lever will 125 130

oscillate said looper supporting shaft and move the same endwise, and means for shifting the position of the fulcrum support on the lever for varying the extent of lateral movement only imparted to the looper.

3. A looper mechanism for sewing machines including in combination, a looper, a looper supporting shaft carrying said looper, a lever connected to said looper, an operating shaft extending at right angles to the looper supporting shaft, a crank carried by said operating shaft to which said lever is connected, a single fulcrum support connected to said lever intermediate the ends thereof and arranged so that said lever both oscillates said looper supporting shaft and moves the same endwise, means for positively shifting the position of the fulcrum support on the lever for varying the extent of lateral movement only imparted to the looper from said lever, and means for locking the fulcrum support in its adjusted positions.

4. A looper mechanism for sewing machines including in combination, a looper, a supporting shaft therefor, an operating shaft arranged at right angles to the supporting shaft for the looper, an arm projecting from the looper supporting shaft having a ball on its outer end, a crank carried by the operating shaft and having a ball on its outer end, a lever having ball socket connections with the arm and the crank, a fulcrum supporting arm connected to the lever intermediate its ends so as to oscillate in a plane lengthwise of the lever, an oscillating sleeve in which said arm is mounted and capable of moving freely endwise, said sleeve being mounted to oscillate about an axis parallel with the looper support, and means whereby the connection of the fulcrum arm to the lever may be shifted.

5. A looper mechanism for sewing machines including in combination, a looper, a supporting shaft therefor, an operating shaft arranged at right angles to the supporting shaft for the looper, an arm projecting from the looper supporting shaft

having a ball on its outer end, a crank carried by the operating shaft and having a ball on its outer end, a lever having ball socket connections with the arm and the crank, a fulcrum supporting arm connected to the lever intermediate its ends so as to oscillate in a plane lengthwise of the lever, an oscillating sleeve in which said arm is mounted and capable of moving freely endwise, said sleeve being mounted to oscillate about an axis parallel with the looper support, a screw connected to the lever so that the same may be rotated without endwise movement, a sleeve on the lever to which said fulcrum arm is pivoted, said screw having a threaded connection with the sleeve whereby the turning of the screw positively moves the sleeve endwise of the lever.

6. A looper mechanism for sewing machines including in combination, a looper, a supporting shaft therefor, an operating shaft arranged at right angles to the supporting shaft for the looper, an arm projecting from the looper supporting shaft having a ball on its outer end, a crank carried by the operating shaft and having a ball on its outer end, a lever having ball socket connections with the arm and the crank, a fulcrum supporting arm connected to the lever intermediate its ends so as to oscillate in a plane lengthwise of the lever, an oscillating sleeve in which said arm is mounted and capable of moving freely endwise, said sleeve being mounted to oscillate about an axis parallel with the looper support, a screw connected to the lever so that the same may be rotated without endwise movement, a sleeve on the lever to which said fulcrum arm is pivoted, said screw having a threaded connection with the sleeve whereby the turning of the screw positively moves the sleeve endwise of the lever, and means for positively clamping the sleeve to the lever.

In testimony whereof, I affix my signature.

JAMES R. MOFFATT.
